UNITED STATES PATENT OFFICE.

WILLIAM A. MARSCHKE AND FREDRICH W. MARSCHKE, OF INDIANAPOLIS, INDIANA.

CONTROLLER.

1,221,345.

Specification of Letters Patent.

Patented Apr. 3, 1917.

Application filed December 24, 1915. Serial No. 68,498.

To all whom it may concern:

Be it known that we, WILLIAM A. MARSCHKE and FREDRICH W. MARSCHKE, citizens of the United States, residing at 5 Indianapolis, in the county of Marion and State of Indiana, have invented a new and useful Controller, of which the following is a specification.

It is the object of our invention to provide a starter for electric motors, which shall be simple and inexpensive, efficient and sure in operation, and will serve to make and break the circuit by a snap switch action and automatically to increase the electro-magnetic force impressed on the motor after the closing of the circuit; and to make the apparatus readily controllable by the operator's foot so that he may have his hands free for other work.

20 The accompanying drawings illustrate our invention. Figure 1 is a front elevation of a starter embodying our invention, showing in section the oil tank in which the switch contacts are immersed; Fig. 2 is a side elevation of such starter, with the oil tank partly in section and the switch open; Fig. 3 is a detail showing the releasable connection between the rheostat rod and its lifting mechanism; and Fig. 4 is a detail of the 25 switch taken from the same viewpoint as Fig. 2, but with the switch closed.

A suitable upright support 10 carries near its lower end an oil tank 11 in which is mounted a horizontal shaft 12 on which 30 are fixed two movable knife blade contacts 13 and 14, which are insulated from the shaft 12 by insulation 15. The lower ends of these knife blades 13 and 14 are movable into and out of engagement with fixed contacts 17 and 18, suitably mounted on insulation 19 within the oil tank 11 and connected by metal strips 21 and 22 to binding posts 23 and 24 at the top of the oil tank 11. The 35 movable blades 13 and 14 are provided with binding posts 25 and 26.

On one end of the shaft 12, outside the oil tank 11, is fixed a T-shaped member having an upwardly extending arm 31, a forwardly extending arm 32, and a downwardly extending arm 33. The upwardly extending arm 31 is connected by a tension spring 34 to a fixed pin 35, suitably carried in the stationary frame work, and by a tension spring 36 to the upper end of an arm 37 fixed on a shaft 38 suitably supported below the oil tank 11 and provided with a

forwardly extending arm 39 carrying a foot piece 40 so that it can readily be operated by the operator's foot. The springs 34 and 36 extend in opposite directions from the arm 31, and are normally balanced in their action on such arm. The forwardly extending arm 32 of the T-shaped member carries a roller 41 which may ride on either the upper or lower surface of a projection 42 carried by the arm 37, so as to prevent movement of the shaft 12 save when the arm 37 is in one or the other of its extreme positions. The arm 37 and foot lever 39 are suitably biased in a clockwise direction (Figs. 2 and 4), as by the weight of associated parts (of which more hereafter), or by a tension spring 43 connecting such lever and a fixed pin 44 suitably supported on the main frame. The downwardly extending arm 33 of the T-shaped member is provided with an inturned flange 45 which strikes a cushion 46 mounted on the side of the oil tank 11 to take the shock when the switch is opened as hereinafter described.

When the foot lever 39 is in its normal position, the springs 34 and 36 are both contracted and the T-shaped member is in the position shown in Fig. 2, with the switch open. When now the operator steps on the 40 foot piece 40 and depresses the lever 39, he tends to stretch both springs 34 and 36, but before there is any material movement of the T-shaped member the upper surface of the projection 42 passes under the roller 41 and prevents such T-shaped member and the movable switch contacts from moving in a counterclockwise direction (Figs. 2 and 4), until the foot lever 39 and lever 37 have about reached their limit of movement in 45 that same direction. By this time, the spring 36 is well tensioned, and the spring 34 is still under practically no tension. When the lever 37 reaches its limit of movement as aforesaid, the projection 42 passes out from under the roller 41, being shown just on the verge of doing so in dotted lines in Fig. 2, whereupon the restraining action on the T-shaped member and movable switch contacts is removed and the spring 50 42 contracts to throw the shaft 12 and parts carried thereby to the position shown in Fig. 4, or in other words to close the switch, which is done with a snap action. When now the operator releases the foot lever 39, 55 such foot lever and the arm 37 return in a clockwise direction from the position shown

in full lines in Fig. 4 toward the position shown in full lines in Fig. 2, being moved in such direction by reason of their aforesaid bias. As this movement starts, there is a 5 tendency to diminish the tension on both springs 34 and 36, but before there can be any material movement of the shaft 12 and parts carried thereby, the under surface of the projection 42 passes over the roller 41 and effectually locks the shaft 12 and its associated parts from movement until the arm 37 practically reaches its limit of movement in a clockwise direction (Figs. 2 and 4). When the arm 37 does reach its limit of 15 movement in such clockwise direction, the projection 42 passes off the roller 41, being shown on the verge of doing so in dotted lines in Fig. 4, and this releases the shaft 12 and parts carried thereby. At this point, 20 the spring 36 is practically fully contracted, whereas the spring 34 remains under substantially full extension, so that when the releasing action takes place the spring 34 contracts to throw the shaft 12 and parts carried thereby in a clockwise direction 25 (Figs. 2 and 4) to open the switch with a snap action.

Mounted on a strip of insulation 50 carried by the frame 10 above the oil tank 11 are a series of contacts 51 and a single contact 52 opposite them, and the single contact 52 may be connected to any one of the series of contacts 51 by a cross-connecting bar 53 having carbon brushes 54 which are spring-35 pressed outward into engagement with the contact 52 and the series of contacts 51. The cross-connecting bar 53 is carried by and insulated from a vertically reciprocable rod 55, which also carries a laminated contact piece 56 which when the cross-connecting bar 53 is in engagement with the lowermost contact 51 interconnects two stationary contacts 57 and 58 carried by the insulation 50 and connected to such lowermost contact 40 51 and to the contact 52 respectively. On the lower end of the reciprocable rod 55 is the piston of a dash pot 60, which retards downward movement of the rod 55 while permitting a free upward movement thereof, in the 45 usual manner of such dash pots. The rod 55 is prevented from turning by a screw 61 which projects into a longitudinal slot in the rod 55. The upper end of the reciprocable rod 55 is provided with a circumferential 50 shoulder 63, which may be engaged by teeth 64 carried by flat springs 65 which join a collar 66 freely slidable on the rod 55 and a yoke 67 carried by a lever 68 pivoted on a fixed pin 69 near the top of the main frame 60 10. The springs 65 are also provided with cams 70 which when the yoke 67 is moved upward engage a camming member 71 fixed in proper position on the main frame 10 and spread the springs 65 apart so as to disengage 65 15 the teeth 64 from the shoulder 63. The

lever 68 is suitably biased in a counterclockwise direction (Fig. 1) as by a tension spring 72, but is connected by a link 73, a lever 74, and a link 75 of adjustable length to a rearwardly extending arm 79 from the arm 37, so that as the foot lever 39 is depressed to move the arm 37 from full to the dotted line positions shown in Fig. 2 the lever 68 is moved from the full to the dotted line positions in Fig. 1, and vice versa. It is in the dotted line position of the lever 68 (Fig. 1) that the teeth 64 are disengaged from the shoulder 63.

The binding posts 24 and 23 are connected by wires 80 and 81 to the supply mains 80 82. The binding post 26 is connected by a wire 83 to one terminal of the field windings 84 and also to one brush of the armature 85 of the motor to be controlled. The other brush of the armature 85 is connected by a 85 wire 86 to a binding post 87 on the contact 52. The other terminal of the field windings 84 is connected by a wire 88 to a binding post 89 on the insulation 50. The binding post 89 is connected by a wire 90 to the lowermost of the contacts 51, and by a wire 91 to the binding post 25. A variable resistance 92 has its ends connected to the uppermost and lowermost of the contacts 51 and intermediate points along it connected to 95 the intermediate contacts 51.

When the operator depresses the foot lever 39, he moves the arm 37 from the full line position shown in Fig. 2 to the full line position shown in Fig. 4, and at the same time 100 moves the lever 68 and the reciprocable rod 55 and associated parts from the full line to the dotted line position shown in Fig. 1. The reciprocable rod 55 reaches its uppermost position, with the cross-connecting bar 105 53 in engagement with the uppermost contact 51, at about the time the projection 42 passes out of engagement with the roller 41 and allows the switch to snap closed to close the motor circuit, so that the entire resistance 92 is in the circuit of the armature 85 and reduces the electro-motive force impressed on such armature from that of the supply mains 82. At about the same time 110 that the switch snaps closed, the camming member 71 and cams 70 cause the teeth 64 to be disengaged from the shoulder 63, thus disconnecting the reciprocable rod 55 from the lever 68 and allowing such rod to start downward, under the action of gravity and retarded by the dash pot 60. As the reciprocable rod 55 moves downward, it comes successively into engagement with the contacts 51, thus cutting out the sections of the resistance 92 and progressively increasing 115 the electro-motive force impressed on the armature 85, but doing so sufficiently slowly to allow the motor to gain in speed sufficiently to develop a counter electro-motive force sufficient to prevent too great a cur- 120 125 130

rent through the armature. When the cross-connecting bar 53 reaches the lowermost contact 51, the laminated contact 56 interconnects the contacts 57 and 58, and as the 5 whole resistance 92 is now cut out the full 10 electro-motive force of the mains 82 is impressed on the armature 85.

When it is now desired to stop the motor, 10 the operator releases the foot lever 39, allowing the parts to return to their normal position and the switch to open, and causing the teeth 64 again to engage the shoulder 63 to reconnect the reciprocable rod 55 and lever 68 for the next starting operation.

15 We claim as our invention:

1. A starter for electric motors, comprising the combination of a switch, a reciprocable member for varying the impressed electro-motive force, said reciprocable member being biased in a direction to increase said impressed electro-motive force, a releasable mechanical connection between said switch and said reciprocable member for moving said reciprocable member against 25 its bias as said switch is moved from open to closed position, and means for releasing said mechanical connection upon the closing of the switch so as to permit said reciprocable member to be moved by its bias to 30 increase said impressed electro-motive force.

2. A starter for electric motors, comprising the combination of a switch, a reciprocable member for varying the impressed electro-motive force, said reciprocable member being biased in a direction to increase said impressed electro-motive force, a releasable mechanical connection between said switch and said reciprocable member for moving said reciprocable member against its 35 bias as said switch is moved from open to closed position, means for releasing said mechanical connection upon the closing of the switch so as to permit said reciprocable member to be moved by its bias to increase 40 said impressed electro-motive force, and means for retarding the movement of said reciprocable member in the direction in which it is biased.

3. A starter for electric motors, comprising the combination of a switch, a reciprocable rod biased in one direction, retarding means for retarding the movement of said rod in the direction in which it is biased, means controlled by the position of said rod 55 for varying the impressed electro-motive force, said rod being provided with a shoulder, a member movable as the switch is opened and closed and provided with a tooth for engaging said shoulder to move said rod against its bias as the switch is closed, and camming means for disengaging 60 said tooth from said shoulder upon the closing of said switch.

4. A starter for electric motors, comprising the combination of a switch, a reciprocable rod biased in one direction, means controlled by the position of said rod for varying the impressed electro-motive force, said rod being provided with a shoulder, a member movable as the switch is opened 65 and closed and provided with a tooth for engaging said shoulder to move said rod against its bias as the switch is closed, and camming means for disengaging said tooth from said shoulder upon the closing of said 70 switch. 75

5. A starter for electric motors, comprising a switch, operating mechanism for producing a snap opening and closing of said switch, a reciprocable rod biased in one direction, means for retarding the movement of said rod in the direction in which it is biased, means controlled by the position of said reciprocable rod for controlling the impressed electro-motive force and producing maximum 80 impressed electro-motive force when said rod is at its limit of movement in the direction in which it is biased, said rod being provided with a shoulder, a member connected with the operating mechanism for 85 said switch and provided with a tooth for engaging said shoulder, said tooth and shoulder coöperating to move said rod against its bias as said switch-operating mechanism is moved to produce closing of the switch, 90 and camming means for disengaging said tooth from said shoulder when said switch-operating mechanism reaches the position in which it causes the switch to snap closed. 95

6. A starter for electric motors, comprising a switch, operating mechanism for producing a snap opening and closing of said switch, a reciprocable rod biased in one direction, means controlled by the position of said reciprocable rod for controlling the 100 impressed electro-motive force and producing maximum impressed electro-motive force when said rod is at its limit of movement in the direction in which it is biased, said rod being provided with a shoulder, a member 105 connected with the operating mechanism for said switch and provided with a tooth for engaging said shoulder, said tooth and shoulder coöperating to move said rod against its bias as said switch-operating mechanism is moved to produce closing of the switch, 110 and camming means for disengaging said tooth from said shoulder when said switch-operating mechanism reaches the position in which it causes the switch to snap closed. 115

In witness whereof, we have hereunto set our hands at Indianapolis, Indiana, this 21st day of December, A. D. one thousand nine hundred and fifteen.

WILLIAM A. MARSCHKE.
FREDRICH W. MARSCHKE.
